UNITED STATES PATENT OFFICE

FRANK HEGEWALD, OF IRVINGTON, NEW JERSEY, ASSIGNOR TO KREMENTZ & COMPANY, A COPARTNERSHIP CONSISTING OF GEORGE K. KREMENTZ AND JULIUS A. LEBKUECHER, OF NEWARK, NEW JERSEY.

METHOD OF CLOSING TUBULAR BODIES.

1,089,339.

Specification of Letters Patent. Patented Mar. 3, 1914.

Application filed March 31, 1913. Serial No. 757,797.

To all whom it may concern:

Be it known that I, FRANK HEGEWALD, a citizen of the United States, residing at Irvington, in the State of New Jersey, have 5 invented certain new and useful Improvements in Methods of Closing Tubular Bodies, of which the following is a clear, full, and exact description.

This invention relates to an improved 10 method of closing the end of a tubular structure, which is provided with a flange at one end. It has a particular value in the manufacture of jewelry, such as collar, cuff, shirt and stud buttons.

15 The object of the invention is to permit the manufacture of such articles as above set forth, particularly out of one piece of metal, so that that part of the device which heretofore has remained open to catch dirt 20 or the like may be absolutely sealed to make a more sightly and a more sanitary device.

For a great many years a collar button known as the Krementz button has been upon the market in which the tubular shank 25 connects the closed button end of the device, while surrounding the tubular shank at the other end is a flange turned over and crimped in at the outer edge. This has heretofore presented an open hole at the end of the 30 tube adjacent the flange. It is the object of this invention to provide a method of closing this hole, whereby the improved product set forth herein can be obtained.

In carrying out the invention the tube 35 with its outstanding flange is set into a rapidly rotating die, the die surrounding the shank, the flange projecting above the face of the dies; then while the die and the flange tube are rotating, a tool, preferably consisting of a rounded wheel, is forced down upon the outer periphery of the flange, bending it 40 down onto the face of the flange. The tool is then moved radially inward, maintained a definite distance from the face of the flange, 45 either by feel on the part of the operator or by mechanical contrivance, and it pushes a circular or spiral wave of metal inward toward the tubular center until there is formed surrounding the tubular center an upstanding circular wall of metal above the plane 50 of the disk. At this point, while not necessary, it is advisable to relieve part of the pressure of the wheel as against the face

of the disk, and continue the motion of the wheel toward the center, going backward 55 and forward toward the center with more or less pressure until this upstanding wall has been ironed into, and the metal thereof caused to flow into the open tubular end, closing the same thoroughly without having 60 in any way lessened the cross-sectional area between the flange and the tubular shank, thus it will be seen I produce out of one piece, a tube, a flange and an inturned filling plug all integral, out of the same piece 65 of metal without having changed the strength at the point of joinder.

The scope of my invention will be pointed out in the claims.

In the accompanying drawings: Figure 1 70 is a plan view of a portion of an ordinary lathe and tool holder equipped for the practising of this invention. Fig. 2 is a central sectional view of the die for holding the article. This is shown as at the beginning 75 of the operation. Fig. 3 is a view similar to Fig. 2, showing a further step in the operation. Fig. 4 is a view similar to the preceding two figures showing a third degree 80 of carrying out the operation. Fig. 5 shows 80 a fourth position of completion. Fig. 6 shows the finishing of the article.

As shown in the drawings, the ordinary lathe chuck 1 is provided with a two-part die 3—4 adapted through its center bore to 85 take the shank of a tube of a stud or other button. The button is shown in the succeeding figures as comprised of a hollow tubular shank 5 with a dished flange 6. The lathe chuck is rotated at a high speed, and in the 90 tool holder a wheel 7 loosely mounted on its shaft 8 is caused to impinge first upon the outer rim of the dished flange 6, as shown in Fig. 2, to press the outer edge down into position shown in Fig. 3 forming a wave 95 in front of the tool 7 as indicated at 8 in Fig. 3. While I have shown in Fig. 1 the wheel 7 as mounted in the chuck for movement inwardly, and sidewise with its motion toward the chuck prevented by a stop 9 so as to 100 limit the sidewise motion of the wheel to that shown in Fig. 3, so that the space between the face of the die and the periphery of the wheel will be at all times equal to the width of the flange, nevertheless I find that 105 the tool may be held in the hand and the

flange and shank rotated by any suitable means when the skill of the workman by the "feel" of the tool can carry out the entire operation with entire success. After the 5 device has placed the flange in the position of Fig. 3, and provided a wave 8, the wheel is moved radially inward to force the wave along into some such shape as shown in Fig. 4 at 9. This motion is continued farther, 10 until the wave is forced over into the position shown in 10 of Fig. 5, when it is often desirable to ease off the pressure and iron down the top of the wave 10 to fill the metal down into the center and into the corners 15 of the dies 11 to produce the effect of Fig. 6. To accomplish this, while it may be done at times by the single passage of the roller across the tube, I find it advisable to release the pressure when the device reaches such a 20 position as shown in Fig. 5, and then to go backward and forward radially until the button is formed into the shape shown in Fig. 6.

Although no claims are made in this application for the article as distinguished from the method of making it, I do not intend to abandon my right to make such 25

claims in another application to be filed hereafter.

I claim as my invention:

1. The herein described method of closing the opening in a tube having a flange at one end consisting of rotating the tube and flange, bringing pressure to bear from the outside of the flange inwardly to cause 35 an upstanding wave of metal at the center, and then forcing said wave of metal into and across the open ended tube.

2. The herein described method of closing the open end of a tubular shank provided 40 with a flange consisting of rotating the shank and flange in a suitable die, the flange being a distance away from the face of the die, then applying a tool from the outer end of the flange inwardly to force said 45 flange down upon the face, then moving said tool radially toward the center to force a wave of metal into and across the open hole.

Signed at Newark in the State of New Jersey this 26th day of March 1913.

FRANK HEGEWALD.
